(57) **CLAIM**

The ornamental design for a wireless charger, as shown and described.

DESCRIPTION

FIG. 1 is a front, right and bottom perspective view of a wireless charger showing my new design;

FIG. 2 is a front perspective view thereof;

FIG. 3 is a back view thereof;

FIG. 4 is a left view thereof;

FIG. 5 is a right view thereof;

FIG. 6 is top plan view thereof;

FIG. 7 is bottom plan view thereof;

FIG. 8 is a perspective views of FIG. 1, shown in a usage position; and,

FIG. 9 is another perspective view, shown in a second usage position.

The broken lines in the drawings illustrate portions of the wireless charger that form no part of the claimed design.
